G. WHITE.

BOAT.

APPLICATION FILED NOV. 17, 1908.

919,102.

Patented Apr. 20, 1909.

UNITED STATES PATENT OFFICE.

GLENN WHITE, OF ASHTABULA, OHIO.

BOAT.

No. 919,102.

Specification of Letters Patent. Patented April 20, 1909.

Application filed November 17, 1908. Serial No. 462,997.

To all whom it may concern:

Be it known that I, GLENN WHITE, a citizen of the United States, and a resident of Ashtabula, in the county of Ashtabula and 5 State of Ohio, have invented new and useful Improvements in Boats, of which the following is a full, clear, and exact description.

My invention relates to boats, and it has 10 for its object to provide a boat with a series of hydroplanes which are spaced apart and are pivoted to the bottom of the boat, there being means provided to hold the hydroplanes in operative position.

15 Another object of the invention is to provide an improved form of hydroplanes.

Still other objects of the invention will appear in the following complete description.

20 In this specification I will describe the preferred form of my invention, but it will be understood that I do not limit myself thereto, as I consider myself entitled to all forms and embodiments of the invention 25 which may be held to fall within the scope of the appended claims.

Reference is to be had to the accompanying drawings, forming a part of this specification, in which similar characters of reference indicate corresponding parts in all 30 the figures, in which—

Figure 1 is a side elevation of my invention; Fig. 2 is an enlarged transverse sectional view thereof; and Fig. 3 is an enlarged plan view of one of the hydroplanes, a portion being broken away to show the manner of its construction.

By referring to the drawings, it will be seen that the body 1 of the boat is of the 40 usual form, although preferably it is in the general shape of an auto-boat, with a flat bottom 2, and straight downwardly converging sides 3. To the bottom of the boat are pivoted a plurality of hydroplanes 4, 45 each of the hydroplanes being wedge-shaped and being pivoted to the bottom of the boat at the apex of the wedge; the top 5 and bottom 6 of the hydroplane being flat and the bottom 6 of the hydroplane being longer 50 than the top 5, so that the rear end 7 of the hydroplane will form with the bottom 6, an acute angle.

Each of the hydroplanes is preferably constructed of galvanized iron and is air-tight.

55 A rod 8 is secured to each of the hydroplanes near its apex by which it is pivoted to the

bottom of the boat. Ears 9 project at either side from the tops and the bottoms of the hydroplanes, and these ears have orifices 10 therein, in which rods 11 are disposed, the 60 rods 11 being secured to the bottom of the boat and having threads thereon and nuts 12 which mesh therewith, the nuts 12 being adapted to screw against the ears 9 to hold the hydroplanes at a predetermined angle 65 with reference to the bottom of the boat. A propeller shaft 13 is so disposed with reference to the boat that the propeller 14 will be under water at all times even when the water line is at the dotted line 15, which is the case 70 when the boat is under way, the line 16 showing the water line when the boat is at rest. When the boat is driven through the water, the hydroplanes 4 tend to lift the boat from the water and when the boat is propelled at a 75 sufficiently high rate of speed, the boat will be lifted completely out of the water, only a portion of the hydroplanes being submerged.

Having thus described my invention, I claim as new and desire to secure by Letters 80 Patent:

1. A boat, a hollow, air-tight, wedge-shaped hydroplane pivoted to the bottom of the boat, and means for holding the free end of the hydroplane in a predetermined position with reference to the boat. 85

2. A boat, a hollow, air-tight, hydroplane pivoted to the bottom of the boat, and means for holding the free end of the hydroplane in a predetermined position with reference to the boat. 90

3. A boat, and a hollow, air-tight, wedge-shaped hydroplane secured to the bottom of the boat with its top forming an angle therewith. 95

4. A boat, and a hollow, air-tight, hydroplane secured to the bottom of the boat with its top forming an acute angle with the bottom of the boat.

5. A boat, a wedge-shaped hydroplane secured to the bottom of the boat, and a top forming with the bottom of the boat an acute angle. 100

6. A boat, and a hollow, air-tight, wedge-shaped hydroplane secured to the bottom of the boat with its apex in contact therewith and its upper surface forming an acute angle with the bottom of the boat, the rear end and the bottom of the hydroplane forming an acute angle. 105

7. A boat, and a series of hydroplanes secured with their upper surfaces disposed at 110

- angles to the bottom of the boat, the length of each of the inner hydroplanes being sufficient for it to fill substantially the gap between the neighboring hydroplanes.
- 5 8. A boat, a series of hydroplanes pivoted to the bottom of the boat, the length of each of the inner hydroplanes being sufficient for it to fill substantially the gap between its neighboring hydroplanes, and means for securing the hydroplanes with their upper surfaces at desired angles to the bottom of the boat.
- 10 9. A boat, and a series of hollow air-tight
- hydroplanes secured to the bottom of the boat, the rear end and the bottom of each of the hydroplanes forming an acute angle, the length of each of the inner hydroplanes being sufficient for it to fill substantially the gap between its neighboring hydroplanes.
- In testimony whereof I have signed my name to this specification in the presence of two subscribing witnesses.

GLENN WHITE.
